TUBE BENDING MACHINE

Hans Schmidt, Aurora, Ill., assignor to Pines Engineering Co., Inc., Aurora, Ill., a corporation of Illinois
Filed Nov. 19, 1962, Ser. No. 238,646
7 Claims. (Cl. 153—40)

The present invention relates to improvements in bending machines and is particularly concerned with the novel construction and assembly of such a machine in which is provided means of novel construction for selectively locking the bending or pressure die holder to the bending form for joint rotation during a bending operation.

More particularly, the exemplary bending machine herein disclosed includes a base structure upon one end of which is mounted a rotatable bending form, a rigid clamp die holder, and a bending or pressure die holder. The latter is mounted for free rotation about the axis of the bending form and it embodies novel hydraulic pressure actuated means for locking the pressure die holder and the bending form together for joint rotation during a bending operation. Such locking and joint rotation is desired to avoid distortion to the work piece as so often occurs while the work piece is being wrapped around a stationary bending form. In the present disclosure, the pressure die holder can be unlocked and returned to its initial position after completion of a bending operation without returning the bending form to its initial position. Because of this structure, the bending form is rotatably driven through and by movement of and in harmony with rotation of the pressure die holder, thus eliminating all slippage or drag during a bending operation.

It is therefore an object of the invention to provide a bending machine having the structural characteristics outlined hereinabove.

Another object of the invention is to provide, in a bending machine, novel means for selectively locking the movable pressure die holder to the bending form during a bending operation.

Another object is to provide a pressure die holder with novel means to lock it to a bending form.

Another object is to provide novel hydraulically actuated lock means.

Another object is to provide a machine having the features described hereinabove which is not expensive to manufacture, is simple in its construction and operation, is easy to operate, and is very efficient and effective for the purpose intended.

With the foregoing and such other objects in view, which will appear as the description proceeds, the invention consists of certain novel features of construction, arrangement and combination of parts hereinafter fully described, illustrated in the accompanying drawings, and particularly pointed out in the appended claims, it being understood that various changes in form, proportion, size and minor details of the structure may be made without departing from the spirit of the invention.

Referring to the drawings in which the same characters of reference are employed to identify corresponding parts:

FIG. 1 is a plan view of one end of a bending machine, showing the bending form, stationary clamp die holder, and rotatable bending or pressure die holder, the latter being shown in bending position in broken lines;

FIG. 2 is an enlarged vertical sectional view taken substantially on line 2—2 of FIG. 1, and showing the bending form locked to the pressure die holder for rotation therewith;

FIG. 3 is a fragmentary view similar to FIG. 2, and partly in elevation, showing the parts in unlocked position; and,

2

FIG. 4 is a detail sectional view taken on line 4—4 of FIG. 2.

Referring to the accompanying drawings, the bending machine illustrated is of a type used for bending tubular, bar or rod stock. The machine comprises essentially a base frame structure 11 including, at one end, a nose housing 12 in and about which a bending form 13 and pressure die holder 14 are mounted for rotation. The machine also includes a rigid clamp die holder 15 arranged rearwardly of the nose housing which carries clamp dies movable into and out of engagement with a work piece 16, illustrated in FIG. 1 by a light broken line, being fed longitudinally along the machine base toward and beyond the nose housing 12.

As is well understood, a work piece 16, such as a length of tubing or bar or rod stock, is fed into position against the channelled perimeter of the bending form 13 whereupon the pressure or bending die 17, illustrated in FIG. 2 only, is brought into tight clamping engagement with the workpiece 16 upon manipulation of the toggle assembly 18 generally shown in FIG. 2. The pressure die 17 then is rotated about the axis of the bending form 13, as by means and in a manner to be described presently, so as to wrap the work piece around said bending form. During this rotational movement of the pressure die, the support holder 14 is locked to the bending form or its mounting so as to rotate the bending form therewith. Upon completion of the bending operation, the pressure die holder is unlocked and said structure is freed from the bending form mounting so as to be free to be returned to its initial position without carrying the bending form therewith.

More specifically, the nose housing 12 provides a journal in which both the bending form 13 and pressure die holder 14 are mounted. As shown, the nose housing 12 is hollow and has upper and lower walls 19 with vertically aligned apertures through which a bearing sleeve 21 extends and which is journaled therein for free rotation in anti-friction bearings 22. A trunnion 23 is freely journaled in and extends through bearing sleeve 21 and is formed on its upper end with a disc 24 having a tangential flat area 25 (FIG. 1) on its perimeter. This area is formed with a radial notch 26 for a purpose to be explained presently. The bending form 13 is mounted on top of said disc 24 and is secured firmly thereto for rotation with trunnion 23 as by means of a stud 27 and nut 28. The bending form 13 may be removed upon removal of nut 28 so as to be replaced by a bending form of a different size.

The bearing sleeve 21 has welded or otherwise secured firmly to it, preferably at its upper end as at 29, one end of an arm 31 comprising a part of the bending die holder 14. As shown, the bending die holder 14 is substantially rectangular in shape and it has, along the upper edge of its vertically depending reinforcing webs 32, a U-shaped trough 33 that is substantially square in section. The trough is closed at its free end by an end wall 34 which may be secured thereto as by screws 35. A slide plate 36 is seated over the open top of the U-shaped trough and it has an integral cylindrical body 37 depending into said trough. The cylindrical body 37 is closed at one end by an end wall 38 and its other end is open to receive therein a cylinder assembly 39 now to be described.

This assembly 39 comprises a cylindrical wall 41, having an integral end wall 42 that is abutted against and secured to the end wall 38 of body 37 as by screws 43. The other end of said cylindrical wall 41 mounts a cap plate 44, secured to said wall by screws 45, including a packing gland 46. A piston rod 47 extends through the packing gland as shown, and mounts a piston 48 within cylindrical wall 41 which, with its end wall 42 and cap plate 44, constitutes a cylinder for said piston.

The projecting end of said piston rod is anchored firmly in the trough end wall 34. The piston rod has an axial passageway 49 to which is connected a fluid line 51 leading from any suitable fluid pressure source not shown.

The slide plate 36 has an end portion extending beyond the cylinder end wall 42, and it has a substantially rectangular tooth or lug 52 on its free end. This lug 52 is adapted, when fluid is admitted into cylinder 41, to engage in the radial notch 26 for locking the pressure die holder 14 to the bending form for rotation in unison. When negative pressure is present within the cylinder, the lug 52 is withdrawn from notch engagement so that the pressure die holder 14 may be rotated about its axis independently of the bending form 13.

The plate 36 has, at its end remote from lug 52, an upstanding boss 53 mounting an adjustable stop screw 54, and the top surface of said plate has a longitudinally extending slot 55 in which the pressure die toggle assembly 18 is mounted. This assembly comprises a backup block 56 and a slide block 57 connected by a manually actuated toggle linkage 58. The slide block 57 mounts the pressure die 17 that is adapted to cooperate with bending form 13 for bending a work piece 16 about the latter when the pressure die is carried through an arc about the axis of the bending form as, for example, from the full line position to the broken line position illustrated in FIG. 1.

Rotation of the pressure die holder 14 is effected through the provision of a sprocket 62 on bearing sleeve 21 which has a chain 63 (FIG. 1) engaged therewith and adapted to be driven selectively when bending movement or return movement of the holder is required. The drive means for chain 63 is conventional and is not shown.

It should be evident that novel means and apparatus has been provided for locking the pressure die holder 14 to the bending form and that such means is positive in its operation. Also, when a bending operation is completed, the pressure die holder can be unlocked and returned to its initial position without reverse rotation of the bending form so as to minimize frictional resistance to the return of the parts to normal and possible distortion of the bend formed in the workpiece.

As many possible embodiments may be made in the invention and as many changes might be made in the embodiment above set forth, it is to be understood that all matters hereinbefore set forth or shown in the accompanying drawings are to be interpreted as illustrative and not in a limiting sense.

What I claim and desire to secure by Letters Patent of the United States is:

1. A bending machine comprising a base structure, a bearing sleeve journaled for rotation in said base structure, a pressure die holder integral with and extending radially from said sleeve, a trunnion journaled in said sleeve, a bending form on said trunnion and rotatable therewith, and disengageable means on the pressure die holder to lock said holder to the trunnion for rotation therewith.

2. A bending machine comprising a base structure, a bearing sleeve journaled on an axis therein, a pressure die holder integral with and extending radially from

said sleeve, said sleeve and pressure die holder being rotatable in unison about said axis, a trunnion journaled for free rotation in said sleeve, a forming die integrally connected with said trunnion, a pressure die mounted on the pressure die holder for cooperation with the forming die to bend a workpiece when the pressure die holder is rotated in one direction about its axis, and means to lock the pressure die holder and trunnion for rotation of the bending form during rotation of the pressure die holder in said one direction.

3. A bending machine comprising a base structure having a nose housing at one end, a bearing sleeve journaled on a vertical axis in said nose housing, a pressure die holder integral with and extending radially from said sleeve, a trunnion journaled in said sleeve, a bending form on said trunnion and rotatable therewith, and disengageable means on the pressure die holder to lock said holder to the trunnion for rotation therewith.

4. The bending machine recited in claim 3, in which the means to lock the pressure die holder comprises fluid pressure actuated means on the pressure die holder engageable with said trunnion.

5. A bending machine comprising a base structure having a bearing sleeve journaled on an axis therein, a pressure die holder integral with and extending radially from said sleeve, means to rotate said sleeve and pressure die holder about said axis, a trunnion journaled for free rotation in said sleeve, a forming die integrally connected with said trunnion, a pressure die mounted on the pressure die holder for cooperation with the forming die to bend a workpiece when the pressure die holder is rotated in one direction about its axis, and means to lock the pressure die holder and trunnion for rotation of the bending form during rotation of the pressure die holder in said one direction.

6. The bending machine described in claim 5, in which the lock means comprises a hydraulically actuated latch carried by the pressure die holder.

7. A bending machine comprising a base structure having a bearing sleeve journaled on an axis therein, a pressure die holder integral with and extending radially from said sleeve, means to rotate said sleeve and pressure die holder about said axis, a trunnion journaled for free rotation in said sleeve, a forming die integrally connected with said trunnion, a slide plate mounted on the pressure die holder, a pressure die mounted on said slide plate, means to slide said plate in the direction of the bending form, and means on said slide plate engageable with the trunnion for locking the pressure die holder to said trunnion for rotating the bending form and pressure die holder in unison.
